UNITED STATES PATENT OFFICE.

THOMAS S. WHITE, OF WEST FRANKFORT, AND MARSHALL M. NEAL, OF BENTON, ILLINOIS.

RAILWAY-GATE.

SPECIFICATION forming part of Letters Patent No. 755,263, dated March 22, 1904.

Application filed September 1, 1903. Serial No. 171,506. (No model.)

To all whom it may concern:

Be it known that we, THOMAS S. WHITE, residing at West Frankfort, and MARSHALL M. NEAL, residing at Benton, in the county of 5 Franklin and State of Illinois, citizens of the United States, have invented a new and useful Railway-Gate, of which the following is a specification.

This invention relates to improvements in 10 railway-gates employed for the purpose of guarding railway-tracks and the railway right of way from the intrusion of cattle, horses, and other animals or to prevent cattle or other animals from passing over bridges or trestles 15 or from entering tunnels or cuts and which may also be employed for the purpose of preventing persons from passing over bridges or entering tunnels or other private property of railway companies, and has for its object to 20 improve and simplify the construction of devices of this character.

The invention consists in certain novel features of the construction, as hereinafter shown and described, and specified in the claims.

25 In the drawings illustrative of the invention, in which like reference characters are employed to designate corresponding parts in the several figures, Figure 1 is a sectional side elevation. Fig. 2 is a plan view. Fig. 30 3 is a transverse section, enlarged, taken through one of the rails and its support.

This improved device may be connected to any desired part of the railway-track, either 35 at the entrances of bridges, tunnels, trestles, road-crossings, at points where fences occur at opposite sides of the railway-tracks, and in other localities which it is desired to guard, and it is not desired, therefore, to limit the device to any specific locality along the track, 40 as the device is capable of application at all the various points designated.

At the point where the device is applied a cavity will be formed beneath the track, in which the operating mechanism will be disposed and into which the guard-gate will be depressed while the train is passing, and thus be entirely out of the way and not liable to be struck by the passing train.

When the device is erected upon bridges or trestles, a portion of the space beneath the bridge or trestle will be utilized for the cavity above referred to; but when located at other points a cavity will be specially formed beneath the track.

For the purpose of illustration the device 55 is shown as if erected beneath an otherwise solid portion of the track, with the cavity 10 beneath it and the rails 11 12 supported upon stringers 13 and posts 14 of the ordinary construction.

60 The guard-gate is illustrated at 15, preferably of the usual construction and vertically disposed transversely of the track and reaching to any desired distance upon either side to provide a guard of the required dimensions 65 to meet the requirements of the locality where erected.

When employed to guard bridges, tunnels, or similar structures, the guard-gate will be of sufficient length to completely guard the 70 gap through which the train passes, and when employed in other localities it will be long enough to fill the gap between the adjacent ends of the fences or other structures forming the adjacent inclosures.

75 The gate member will be disposed to be moved vertically relative to the track and when depressed will enter the cavity 10 below the tracks, as indicated by dotted lines in Fig. 1.

80 Located adjacent to the rails 11 12 are trip-rails 16 17, two of the rails being employed reversely disposed and extending in opposite directions, with one of the rails preferably adjacent to the track-rail 11 and the other rail 85 preferably adjacent to the track 12, with their adjacent ends overlapping for a short distance, as indicated in Fig. 2, and with their upper surfaces substantially even with the treads of the rails. These trip-rails 16 17 are 90 precisely alike and are pivoted at their outer ends, as at 18 19, to the supporting-framework of the track and free to move vertically by their inner or adjacent ends. The outer ends of the trip-rails are provided, respectively, with depending arms 20 21, in the 95

lower ends of which the pivots 18 19, by which the trip-rails are supported, are located, as shown in Fig. 1.

The trip-rails 16 17 at the ends next the bars 20 21 are inclined, as shown at 22 23, to provide for the gradual reception of the flanges of the wheels of the approaching trains and prevent jarring or injurious impact from the rapidly-moving train.

10 The arms 20 and 21 and portions of the inclines 22 23 are formed of relatively heavy metal to withstand the strains, while the remainder may be of lighter material, as the strains are less severe toward the free ends of 15 the rails.

The rails 16 17 are stiffened by truss-rods 24 25 and brace-rods 26 27, the truss-rods being provided with suitable turnbuckles to secure the requisite rigidity and forming a truss-like structure to cause the trip-bars to operate without deflection and to resist the strains to which they will be subjected. Mounted for oscillation in the space 10 is a shaft 28, having a short arm 29, connected by a link 30 25 to the rail 17, so that the vertical movement of the rail will oscillate the shaft. A similar shaft 31 is mounted for oscillation beneath the other rail 16 and has an arm 32, connected by a link 33 to the rail 16, so that the vertical 30 movement of the rail will oscillate the shaft.

20 Mounted for oscillation between the shafts 28 and 31 is a third shaft 34, connected by bars 35 36 to the gate 15, which is thereby supported. The shaft 34 is also provided with a 35 U-shaped frame 37, with which arms 38 39, extending, respectively, from the shafts 28 31, movably engage, as shown.

30 The shaft 34 is provided with a weighted arm 40, exerting its force to maintain the rails 17 18 and gate 15 in their upper or operative positions, as shown.

The lengths of the rails 17 18 will be sufficient to insure the presence of at least two wheels of the train upon the rails at all times 45 while the train is passing to prevent any possibility of the release of the rails and levers and the elevation of the gate beneath a passing train. The rails and their inclined ends may be of any required length; but practice 50 has shown that a length of about ten feet for the inclined portions 22 23 and about forty feet for the straight portions fully meet the requirements.

55 The supports for the railway-rails 11 12 will be provided at suitable intervals with guard members 41 to prevent lateral movement of the trip-rails 17 18 without interfering with the vertical movement, as shown more clearly in Fig. 3.

60 The arms 29 32 and bar 39 will necessarily be so proportioned relative to the trip-rails that the depression of either of the latter will depress the gate to the same extent, as will be obvious. By this means it will be obvious 65 that when the trip-rails are depressed the

rock-shaft 34 will be correspondingly rotated in its bearings and the gate 15 withdrawn beneath the track and remain depressed until the train passes.

It will be noted that the trip-rails 16 17 are 70 independently connected to the rock-shaft 34, so that the depression of either one will operate said rock-shaft. By this arrangement when a train runs upon either one of the trip-rails the inner end will be immediately depressed by the flanges of the wheels, this downward movement being communicated to the gate through the connecting-levers and the gate immediately depressed below the line of the railway-rails and remain in that position 75 so long as the train or any portion of it is in contact with the trip-rails, as the weight 40 will be overcome by the weight of the train; but as soon as the train leaves the trip-rails the weight will at once return the gate to its 80 upward position and at the same time restore the trip-rails to their former position ready for the next passing train. By this simple means the device is entirely automatic in its action and will not require the attention of 85 any person to maintain it in operation.

The members 16 17 may be of any suitable shape in cross-section, but must be of ample strength to resist the strains to which they will be subjected, and will be inclined, as 90 above noted, at their ends to cause the car-wheels to run gradually into engagement with them and prevent sudden jars or pounding impacts.

The trip-rails will engage the track-rails 100 sufficiently close to insure the contact of the flanges of the wheels of a passing train and at the same time prevent the lodgment of snow or the formation of ice between the track-rails and trip-rails. 105

The whole structure is extremely simple, easily erected, certain and positive in its action, and will adequately protect and guard the entrances to bridges or tunnels, gaps in fences, and other localities automatically and will 110 not be injuriously affected by the jar or concussion of the passing trains.

To prevent any possibility of the trip-rails 11 12 catching beneath the heads of the track-rails at their upward movements, small guard-blocks 42 will be employed at suitable intervals to fill the gaps between the vertical webs and heads and secured in place, as by bolts 43, as shown in Fig. 3.

Having thus described the invention, what is 120 claimed is—

1. In a device of the class described the combination with railway-track rails, of reversely-disposed trip-rails arranged adjacent said track-rails in position to be operated by a passing train, spaced transversely-arranged shafts disposed between said rails on opposite sides of the gate opening in a plane below the track, and connected respectively with the trip-rails, a shaft disposed intermediately of said spaced 125 130

shafts and in alinement therewith, a weighted arm attached to said intermediate shaft, a yoke member extending laterally from said intermediate shaft on one side and spaced arms extending from the other side, a vertically-arranged gate mounted on the free ends of said spaced arms, arms extending respectively from said spaced shafts and movably engaging said yoke, the arm connecting the remote shaft 10 being curved downwardly to provide for the downward movement of the gate.

2. In a device of the class described the combination with railway-track rails, of reversely-disposed trip-rails arranged adjacent to the track-rails in position to be operated by a passing train, a vertically-movable gate, an operating-shaft disposed transversely in a plane below said track and having a weighted arm at-

tached thereto, connecting means between said shaft and gate, means for connecting said shaft with one of said trip-rails, and a rod connected with said shaft and extending beneath the gate and connected with the other trip-rail, said rod being spaced from said gate a distance sufficient to permit the depression 25 of the gate below the track.

In testimony that we claim the foregoing as our own we have hereto affixed our signatures in the presence of two witnesses.

THOMAS S. WHITE.
